ATTORNEY

UNITED STATES PATENT OFFICE.

GEORGE G. McDONALD, OF ST. ESPRIT, NOVA SCOTIA, CANADA.

ROWBOAT.

1,226,095.

Specification of Letters Patent. Patented May 15, 1917.

Application filed October 30, 1916. Serial No. 128,551.

To all whom it may concern:

Be it known that I, GEORGE G. McDONALD, a subject of the King of Great Britain, residing at St. Esprit, in the Province of Nova Scotia and Dominion of Canada, have invented certain new and useful Improvements in Rowboats, of which the following is a specification.

This invention has reference generally to boats and more particularly relates to a paddle wheel mechanism for propelling boats.

As the primary aim and object the present invention has to provide novel foot operating means for actuating the paddle wheel of a boat so as to propel the boat in an efficient manner.

The invention as an equally important object contemplates the provision of a foot paddle that is detachable from the motion transmitting means to permit of the latter being actuated by hand and consequently permit the operator to reverse the movement of the boat.

Among the other aims and objects of the present invention may be recited the provision of a device of the character mentioned with a view to compactness, and in which the number of parts are few, the construction simple, the cost of production low and the efficiency high.

Other improvements and novel details in the construction and arrangement of parts will be appreciated from the detailed description below, which is to be read in connection with the accompanying drawings forming a part thereof, and wherein I disclose a preferred embodiment of my invention for the purpose of illustration.

The preferred embodiment is illustrated in the accompanying drawings in which:

Figure 1 is a top plan thereof.

Fig. 2 is an enlarged top plan of the mentioned transmitting mechanism, and

Fig. 3 is a detailed elevation of several of the elements of the transmitting and actuating mechanism.

Similar characters of reference are employed in all of the above described views, to indicate corresponding parts.

Referring now more particularly, to the accompanying drawings I provide a boat 1 of any conventional construction. The shaft 2 has its respective ends rotatably

mounted in bearings 3 carried on the upper edges of the side of the boat. Paddle wheels 4, of any conventional construction, are carried by the projecting ends of the shaft 2 and when the shaft is rotated, the paddle wheels 4 will be also rotated and consequently propel the boat.

With a view toward providing suitable means for transmitting rotary movement to the shaft 2 I have connected a gear 5 to the shaft 2 and meshed therewith is a similarly constructed gear 6 carried on a shaft 7. The shaft 7 has its respective ends journaled in suitable bearings 8 mounted in spaced relation in boat and arranged so as to dispose the shaft 7 in spaced parallel relation with the shaft 2. A bevel gear 9 is also carried by the shaft 7 adjacent the opposite end and meshes with a similarly constructed bevel gear 10 carried by a shaft 11. The shaft 11 is arranged longitudinally of the boat 70 and at right angles to the axis of the shaft 2, the respective ends thereof being journaled in suitable bearings 12 also mounted in the embodiment of the boat. A fly wheel 13 is mounted upon the free projecting end 80 of the shaft 11.

In order to rotate the fly wheel 13 and consequently rotate the paddle wheels 4 I have pivotally connected one end of a link 14 to the outer face of the wheel 13 by means 85 of a suitable pin 15, which is eccentrically connected thereto. The opposite end of the link is pivotally connected by means of a pin 16 to the outer end of a foot pedal 17 which has its inner end in turn pivotally 90 mounted by means of a pin 19 to a bracket 18 carried on the bottom of the boat.

The operation of the invention may be reviewed as follows:

Assuming that it is desired to propel the boat forwardly the wheel 13 is engaged by one hand of the operator and its top pushed in a direction away from the foot pedal whereupon the operator may by continually depressing the foot pedal 17 rotate the wheel 100 in the direction of its initial movement. Consequently the gear 10 is rotated and because of the gear 9 which meshes with the gear 10, the shaft 7 is rotated. Movement is transmitted from the shaft 7 to the shaft 2 to consequently actuate the paddle wheel, by means of the meshing gears 5 and 6. If desired the pin 15 may be released when the

operator has become tired by using his foot so as to detach the link 14 whereupon the pin can be again inserted so as to serve as a crank to rotate the shaft 11 in either direction and either propel the boat forward or reverse the movement thereof.

As many changes could be made in the above construction and many apparently widely different embodiment of this invention could be made without departing from the scope thereof, it is intended that all matter contained in the above description or shown in the accompanying drawings shall be interpreted as illustrative and not in a limiting sense. It is also to be understood that the language used in the following claims is intended to cover all of the generic and specific features of the invention herein described and all statements of the scope of the invention which as a matter of language, might be said to fall therebetween.

Having thus described my invention what

I claim and desire to secure by Letters Patent is:—

What I claim is:—

A boat propelling means including a rotatably mounted shaft, paddle wheels thereon, a gear connected to the shaft, another shaft, a gear thereon in mesh with first mentioned gear, another shaft arranged in operable relation with the second mentioned shaft, a fly wheel on the last mentioned shaft, a pivotally mounted foot pedal, a link pivotally connected to the free end of pedal, and a pin for removably, pivotally and eccentrically connecting the free end of the link to the fly wheel, substantially as described.

In testimony whereof I affix my signature in presence of two witnesses.

GEORGE G. McDONALD.
